UNITED STATES PATENT OFFICE.

FRED B. VAUGHN, OF LOS ANGELES, CALIFORNIA; ASSIGNOR, BY DIRECT AND MESNE ASSIGNMENTS, OF ONE-HALF TO IDRIS THOMAS, OF LOS ANGELES, CALIFORNIA.

VALVE APPARATUS.

Application filed April 21, 1924. Serial No. 707,932.

This invention relates to valve apparatus, and while features of the invention may be employed in the construction of valves for various purposes, the invention is especially applicable in valve apparatus used in deep wells. In such wells, it is customary to provide a valve mounted in the flow-pipe at a great depth in the well below which the pump plunger is located. With the usual construction, the valve is mounted in the flow-pipe in such a way that when it is necessary to pull up the polished rod and plunger, it is also necessary to pull up the entire string of pipe constituting the flow-pipe. In deep wells, this involves a loss of time and considerable labor. The general object of this invention is to provide a valve apparatus which will overcome this difficulty and which, while providing an efficient valve in the flow-pipe, is so constructed as to enable the valve to be raised simply by pulling up the polished rod and plunger. A further object of the invention is to construct the valve in such a way that it will occupy a relatively small amount of space and yet provide a relatively large area of opening past the valve member or valve members when they are lifted from their seats; also to provide a stuffing-box connected with the valve body so that the lifting of the valve also raises the stuffing-box.

Further objects of the invention will appear hereinafter.

The invention consists in the novel parts and combination of parts to be described hereinafter, all of which contribute to produce an efficient valve apparatus.

A preferred embodiment of the invention is described in the following specification, while the broad scope of the invention is pointed out in the appended claims.

In the drawing:

Figure 1 is a vertical section through the flow pipe of a well to which my invention has been applied.

Fig. 2 is a cross section through the valve apparatus taken on the line 2—2 of Figure 1, but upon an enlarged scale.

Fig. 3 is also a cross section, but taken on the line 3—3 of Figure 1; this view is also upon an enlarged scale.

Fig. 4 is a developed section taken on the line 4—4 of Figure 3 and partly illustrating the manner in which the invention operates

to give an increased lateral area or lateral passage for the fluid past the valves.

In applying my invention to a deep well, I provide the flow pipe 1 with a special coupling 2 at which the valve is located. In this coupling the valve body is mounted, and in the present instance this valve body 3 is in the form of a plug having a plurality of vertical ports 4 through which the liquid, for example oil, moves upwardly at each up-stroke of the pump piston, which is located below the valve. Each of the ports 4 communicates at its upper end with the corresponding valve chamber 5. Each valve chamber carries a valve member preferably in the form of a ball 6, each ball normally resting upon a seat 7 which is formed by the upper end of the valve opening or port 4.

The valve chambers 5 are formed in the upper face of the plug 3 and they are, of course, of slightly larger diameter than the ball valves which they contain. In order to provide an increased area of outlet for the liquid when the valves rise off their seats I provide a circumferential slot 8 in the upper end of the plug, the center of which preferably coincides with the circumferential pitch line on which the centers of the valve openings 4 are located. This slot 8 opens communication between the valve chambers, and when the balls rise off their seats the liquid flowing up the ports 4 does not have to depend upon the area of the chamber to find exit, but can flow laterally into the slot, as illustrated by the arrows in Figure 4. In this way I provide a greatly increased area of outlet for the liquid when the valves are in their open position, as illustrated in Figure 4.

Any suitable means may be provided for retaining the valves in the valve chambers. For this purpose I prefer to provide a keeper in the form of a perforated plate 9, said plate having large arcuate perforations 10 between which are radial arms 11, each radial arm being disposed over one of the valves and operating as a stop to arrest the upward movement of the valve and prevent its dislodgment from the valve chamber.

In order to provide for lubricating the pump rod or polished rod 12 and at the same time secure the keeper plate 9 in position, I provide a stuffing box 13 (see Figure 1) the lower end of which is provided with

a reduced neck 14 forming a shoulder 15; the plate 9 has an opening 16 through which the neck 14 passes so that the shoulder 15 will seat against the upper face of the plate 5 at the edge of this opening. The lower end of the neck 14 is provided with screw-threads 17. When the stuffing box is tightened up the shoulder 15 will jam on the keeper plate and hold the same rigidly in place.

10 The upper part of the stuffing box 13 carries a suitable vegetable packing 18 held in place by a gland 19 which is pressed down on the packing by a coil spring 20 held in a barrel 21 which is attached by threads 22 15 to the outer side of the stuffing box.

The coupling 2 is provided with a tapered bore 23 and the plug or valve body 3 is tapered so as to fit in this bore by being moved into the same from above.

20 In constructing the valve, it will be evident that the valve openings 4 and the valve chambers can be readily formed by drilling through the upper end of the valve body; the circumferential slot 8 can then be readily

25 formed in the upper face of the plug or valve body 3 by a lathe operation.

It will be evident that this valve apparatus, although the valve members themselves may be small, will afford a relatively large 30 area of outlet for the liquid when the valves are off their seats, because the liquid flows out into the arcuate portions of the slot 8 which form ducts connecting the valve chambers.

35 The lower end of the polished rod 12 carries a pump plunger 24 which is of sufficiently smaller diameter to enable it to pass through the tapered bore 23 when the polished rod is lowered into the well. This 40 plunger may be of any suitable construction and usually includes a valve such as the ball valve 25. If it should be necessary to raise the plunger in order to get access to the same for the purpose of repair, or for 45 any other purpose, it is merely necessary to pull the polished rod from the well. In doing so, when the plunger reaches the valve body 3, it dislodges it from the tapered bore and raises it, together with the stuffing-

50 box, to the mouth of the well. In replacing the polished rod and fixed valve in the well, it is simply necessary to lower the polished rod with the valve plug 3 on the polished rod and supported by the plunger. As soon 55 as the plug 3 reaches the tapered bore 23 it seats itself and the lowering of the polished rod is then continued until it reaches its proper position at the bottom of the well.

60 By locating the valve body 3 at a low level in the well, it will be evident that substantially all the weight of the column of liquid above the plunger can be taken on the valve members at the plug 3, and this tends to eliminate a "whipping" action in the polished rod reciprocating it. The

flow of the oil past the ball valves 6 takes place around the entire area of the under side of each ball so that there is no tendency for sand in the water or oil being pumped to cut or wear the ball valves unevenly. 70

It is understood that the embodiment of the invention described herein is only one of the many embodiments this invention may take, and I do not wish to be limited in the practice of the invention, nor in the 75 claims, to the particular embodiment set forth.

What I claim is:—

1. In a valve apparatus, the combination 80 of a valve body having a plurality of valve chambers with their corresponding valve openings below the valve chambers, and a valve operating in each valve chamber, said body having a circumferential slot in its end with arcuate ducts connecting the valve chambers, said arcuate ducts operating to provide a lateral passage increasing the area for the flow of liquid passing up through the valves.

2. In a valve apparatus for a pump, the combination of a flow pipe, a valve-body carried on the flow pipe, and having a plurality of valve-chambers with their corresponding valve openings, a valve operating in each valve chamber, said body having a circumferential slot in its end with arcuate ducts connecting the valve chambers, said arcuate ducts operating to provide a lateral passage increasing the area for the flow of 90 liquid past the valves.

3. In a valve apparatus for a pump, the combination of a flow pipe, a valve-body carried in the flow pipe, and having a plurality of valve-chambers with their corresponding valve openings, a valve operating in each valve chamber, said body having a circumferential slot in its end with arcuate ducts connecting the valve chambers, said arcuate ducts operating to provide a lateral passage increasing the area for the flow of 100 liquid past the valves, and means above the valves for retaining them in the valve chambers.

4. In a valve apparatus for a pump, the combination of a flow pipe, a valve-body carried in the flow pipe, and having a plurality of valve-chambers with their corresponding valve openings, a valve operating in each valve chamber, said body having a circumferential slot in its end connecting the valve chambers and operating to provide a lateral passage for the liquid past the valves, a pump rod passing through the valve body, a perforated keeper for retaining the valves in their valve chambers, and a stuffing box for the rod above the keeper and supported on the valve body. 110

5. In a valve apparatus for a pump, the combination of a flow pipe, a valve body in the form of a plug carried in the flow pipe 120

- and having a plurality of valve chambers with their corresponding valve openings in the upper end of the plug, a ball valve operating in each valve chamber, said body having a circumferential slot in its end connecting the valve chambers and operating to provide a lateral passage for the liquid past the ball valves, a keeper in the form of a perforated plate seating on the body to retain the ball valves, a stuffing box secured in the upper end of the body and retaining the perforated keeper in position, and a pump rod passing through the said body and through the stuffing box.
6. In a valve apparatus for a pump, the combination of a flow pipe having a coupling in the same with a tapered bore, a valve body in the form of a plug seating in the tapered bore, said valve body having a plurality of vertical openings leading therethrough with valve seats at their upper ends, ball valves received on the seats, said body having a valve chamber corresponding to each ball valve formed in its upper end and having a circumferential slot with arcuate ducts connecting the valve chambers, said arcuate ducts operating to provide a lateral passage increasing the area for the flow of the liquid past the valves, and means for retaining the ball valves in their valve chambers.

Signed at Los Angeles, Calif., this 9th day of April, 1924.

FRED B. VAUGHN.
